(57) **CLAIM**

The ornamental design for an automated external defibrillator case, as shown and described.

DESCRIPTION

FIG. 1 is a top view of an automated external defibrillator case from above;

FIG. 2 is a side view of the automated external defibrillator case from a first side;

FIG. 3 is a side view of the automated external defibrillator case from a second side, opposite the first side;

FIG. 4 is a front view of the automated external defibrillator case;

FIG. 5 is a bottom view of the automated external defibrillator case from below;

FIG. 6 is a rear view of the automated external defibrillator case;

FIG. 7 is a front perspective view of the automated external defibrillator case from above; and,

FIG. 8 is a rear perspective view of the automated external defibrillator case from above.

In FIGS. 1-8, the broken lines represent portions of the automated external defibrillator case that form no part of the claimed design.

1 Claim, 8 Drawing Sheets
